United States Patent

Des. 240,605
Patented July 20, 1976

240,605

WATCH

William Sticker, Hastings House 2A,
Hastings-on-Hudson, N.Y. 10706

Filed Dec. 26, 1974, Ser. No. 536,574

Term of patent 14 years

Int. Cl. D10—02

U.S. CL. D10—38

FIG. 1.

FIG. 2.

FIG. 3.

FIG. 4.

FIG. 5.

FIG. 6.

FIG. 7.

FIG. 8.

FIG. 1 is a top plan view of a watch showing my new design with a typical digital readout at the center;

FIG. 2 is a bottom plan view thereof;

FIG. 3 is a typical end elevational view thereof;

FIG. 4 is a typical side elevational view thereof;

FIG. 5 is a top plan view of a modified form of my new design of FIG. 1 wherein the case is square;

FIG. 6 is a bottom plan view of FIG. 5;

FIG. 7 is a typical end elevational view of FIG. 5; and

FIG. 8 is a typical side elevational view of FIG. 5.

I claim:

The ornamental design for a watch, as shown and described.
